(57) **CLAIM**

The ornamental design for a toilet seat cover, as shown and described.

DESCRIPTION

FIG. 1 is a perspective view illustrating the new design for a toilet seat cover;

FIG. 2 is a front elevation view thereof;

FIG. 3 is a back elevation view thereof;

FIG. 4 is a left elevation view thereof;

FIG. 5 is a right elevation view thereof;

FIG. 6 is a top elevation view thereof;

FIG. 7 is a bottom elevation view thereof; and,

FIG. 8 is a perspective view of the toilet seat cover being used.
The broken lines shown in FIG. 8 of the drawing views represent a toilet bowl and form no part of the claimed design.
